UNITED STATES PATENT OFFICE.

HORACE T. THOMAS, OF LANSING, MICHIGAN.

WINDSHIELD FOR AUTOMOBILES.

Application filed September 15, 1924, Serial No. 737,703. Renewed September 23, 1927.

My invention relates to wind shields for automobiles and an object of my improvements is to provide a wind shield which is simple in construction, water-tight, and 5 noise-proof, and which may be conveniently adjusted to different positions within the required limits.

Wind shields have been pivoted by pins at their side edges, and by metal hinges at their 10 upper edges but these constructions have metal to metal contacts and permit the access of water to the interior of the car and between the parts of the joints. To prevent this, special constructions consisting of curtains, or shields, have been devised. Such 15 previous constructions form rigid and unyielding attachments for the shields.

I have obviated the above recognized defects by providing a connection between the 20 shield and the edge of the opening therefor of integral flexible and resilient material that permits of the angular adjustment of the shield while forming a tight joint between said edges and one that cushions the 25 weight of the shield.

In the accompanying drawings I have shown a construction embodying my invention as applied to an enclosed, or sedan, body.

30 Figure 1 is a front elevation of one-half of a construction embodying my invention and the adjacent parts of the body to which it is attached.

Fig. 2 is an elevation of the same looking 35 from the right of Fig. 1, partly in section.

Fig. 3 is a section to an enlarged scale of the shield and adjacent parts with portions broken away to economize space.

Fig. 4 is an elevation of the construction 40 shown in Fig. 3 looking from the right of the same, the securing parts being shown in broken lines only.

Fig. 5 is a detail section on the line V, V, 45 Fig. 4.

a is the vehicle body. *a*² indicates the opening in the front wall of said body in which the wind shield is fitted.

b is a metal strip secured to the vertical 50 edge of the opening *a*². The construction is the same upon both sides and, therefore, only one side will be described. The strip *b* is turned over and extends in a portion *b*² parallel to itself and for about half the width of said strip (Fig. 5). *c* is a metal 55 strip turned up at its edges to form a

trough *c*⁴. The inner edge extends vertically in a portion *c*³ and the outer edge is turned over and extends horizontally backward, presenting an edge *c*² in the plane of the shield (Fig. 3). The strip *c* is shaped 60 to fit against the lower edge of the opening *a*² and extends the entire distance across the opening. *c*⁵ (Fig. 4) is a hole formed thru the outer wall of the trough *c*⁴, at a position which shall permit any water that may fall into said trough to drain to the outside 65 of the body.

*d*² is the glass of the wind shield and *d* is a frame extending around the glass *d*² and adapted to fit within the opening *a*² 70 and against the walls thereof. The frame *d* is made up in part of two side pieces *d*³ shown most distinctly in Fig. 5, which present cavities *d*⁴ adapted to receive the lateral edges of the glass *d*² and grooves *d*⁵ opening 75 toward the front. *e* is a rubber strip in the cavity *d*⁵. When the shield is in its closed position, the overturned portion *b*², of the strip *b*, enters the cavity *d*⁵ and engages with a tight joint against the outer 80 surface of the rubber strip *e*. *e*² is a strip of rubber fitting in the cavity *d*⁴ and tightly engaging the edge of the glass *d*².

*d*⁶ is the portion of the frame *d* extending along the lower edge of the glass *d*². This has a cavity *d*⁸ opening upward in which is a channel strip of rubber *e*⁴ tightly engaging the lower edge of the glass *d*² in said cavity. The strip *d*⁶ presents at its lower edge a cavity *d*⁷ opening outward and 85 in the bottom of this cavity is a rubber strip *e*³. The edge *c*² of the strip *c* enters the cavity *d*⁷ and engages with a tight joint against the outer surface of the rubber strip *e*³. *d*⁹ is the portion of the frame *d* extending 90 along the upper edge of the glass *d*². This presents a downwardly opening cavity *d*¹⁰, in which the upper edge of the glass *d*² engages with a tight joint by means of the channel rubber *e*⁵ in said cavity. 95

f is a strip of rubber having a downwardly opening cavity, or groove, *f*² therein, which extends throughout its entire length. The rubber strip *f* engages with its upper surface the upper edge of the opening *a*². *f*³ 105 is a strip of metal extending along and engaging the inner wall of the cavity *f*². *f*⁴ indicates securing screws which pass through screw holes in the strip *f*³, their heads engaging the walls of said holes and their 110

shanks engaging the wood at the upper edge of the opening a^2 .

The portion d^9 of the frame d engages for part of its width with a tight joint in the 5 cavity f^2 of the rubber strip f , as shown in Fig. 3.

g is a lug secured through a base plate g^2 to the side d^3 of the frame d and extending at right angles to the wind shield at a 10 side edge thereof.

h (Figs. 3 and 5) is a lug secured through a base plate h^2 at the side wall of the opening a^2 adjacent and parallel to the lug g . h^3 is an arcuate slot in the lug h , the center 15 of the radius of which is at the joint between the frame d and the rubber strip f .

j is a bolt, the shank of which extends through the slot h^3 and through a circular hole in the outer end of the lug g ; the head 20 j^2 of said bolt engaging the outer wall of the lug h adjacent to the slot h^3 . j^2 is a winged nut engaging the threads of the bolt j and the inner surface at the outer end of the lug g .

25 k is a handle upon the frame d by which the wind shield may be moved to adjust it to any position desired.

The mode of using the above described wind shield is as follows:

30 If it is desired to close the front opening entirely, the nut j^2 is loosened and the wind shield forced outward, the edges b^2 of the side pieces b engaging with a tight joint against the rubber strips e and the edge c^2

35 of the lower strip e engaging with a tight joint against the rubber strips e^3 . If it is desired to provide an opening for the admission of air, the nut j^2 is loosened and the lower edge of the shield is drawn inward

40 by means of the handle k , as indicated by broken lines in Fig. 2, the bolt j passing along the arcuate slot, h^3 , and the shield turning about the flexible joint formed by the rubber strip f engaging its upper edge.

45 When a sufficient opening is provided, the nut j is again tightened and the shield is thereby held in its adjusted position, the engagement between the lugs g and h always holding the shield in its proper position during its movement, as well as in engagement 50 between the frame d and the strip f .

Any water that may fall into the trough c^4 is discharged through the aperture c^5 to the outside of the body.

55 It will be noted that there is no hinge and that there can be no noise at the flexible joint of the shield, that the shield can swing to provide as large an opening as is required, that the construction is simple, and that all 60 joints are water tight.

While the construction shown contemplates that the shield opens inward, it is obvious that the shield may open outward if desired.

What I claim is:

1. The combination of a wind shield, an automobile having an opening for said wind shield, and a flexible part joining adjacent edges of said shield and opening and constituting a hinge that shall hold the edge of 70 said shield adjacent to the edge of said opening in position and permit the wind shield to turn about said hinge, said part consisting of a strip of rubber permanently secured to one of said edges and fixedly secured to the other edge by a groove and tongue construction so as to form a tight joint between said edges.

2. The combination of a wind shield, an automobile having an opening for said wind shield, and a flexible part joining adjacent edges of said shield and opening constituting a hinge for said shield, and a separate means adapted to carry the weight of said shield and hold it in position at its different 80 adjusted positions consisting of a pair of lugs one upon the shield and one upon the edge of the opening, and a connection between said lugs guided in an arc of a circle 85 having its center at the line of flexure of said flexible part.

3. The combination of a wind shield, an opening therefor, and a sheet metal strip forming the wall at the lower edge of said opening and turned inward and backward 90 toward its outer edge to present an edge to a vertical surface of said shield, said strip having its opposite edge turned upward, and means for draining water from 95 said strip.

4. The combination of a wind shield, an automobile having an opening for said wind shield, one edge of said opening being provided with a piece of flexible material permanently fixed thereto extending throughout the length of said edge and forming a weather tight joint therewith, said piece of flexible material being provided with a channel along its entire lower edge, one edge 105 of said wind shield slidably engaging in said channel to form a weather tight joint, said shield being adapted to turn at said edge by flexing said material and separate means adapted to support the weight of said shield and hold it in different angular positions to 110 which it may be adjusted.

In testimony whereof, I sign this specification.

HORACE T. THOMAS.
